BOTTLE

Albert C. Petitto, Hudson, Mass., assignor to Foster Grant Co., Inc., Leominster, Mass., a corporation of Delaware

Filed Sept. 24, 1963, Ser. No. 76,712

Term of patent 14 years

(Cl. D58—8)

FIG. 1 is a side elevational view of a bottle, showing my new design;

FIG. 2 is a top plan view thereof;

FIG. 3 is a cross-sectional view thereof taken through lines 3—3 of FIG. 1 and partially shown in phantom for convenience of illustration; and

FIG. 4 is a bottom plan view thereof.

I claim:

The ornamental design for a bottle, substantially as shown.
